SYSTEM FOR TREATING UNIFORM OBJECTS AND A DIFFERENTIAL GEAR FOR SUCH SYSTEM

This invention relates to a system for treating uniform objects and is of the type comprising a plurality of treating stations provided with automatic feeding and conveyor means between successive stations, said conveyor means including storage means for the objects to be treated. Such systems are used in various contexts in industry, particularly in the food industry, where containers must be subjected to a series of treatments, comprising for inst. cleansing, filling, sealing, labelling, packing and, where required, control measures. The various treating stations are usually dimensioned so that their normal operational speed will be below the maximum rate, provision having been made for a certain reserve and for brief suspensions of operation that frequently occur at the individual stations, so that after a suspension of the operation of a single station the working speed of this station may be increased sufficiently to catch up with the output of the other stations. Such regulations, however, previously had to be made manually or by stepwise regulation of a sensing control, and it is the aim of the present invention to provide a treating system where the operational speed of the individual stations is adjusted automatically and in a manner by which any irregularity caused by brief stoppages of the individual stations will be equalized automatically.

This has been achieved according to the invention by providing between a station and the succeeding storage means and between the storage means and the succeeding station an automatic counting device for counting the objects, and that the two counting devices are coupled each to one side of a differential gear provided with a movable member for recording the difference between the numbers of objects registered by the two counting devices, the movable member of the differential gear being coupled to a regulating device for the working speed of the preceding and/or the succeeding treating station.

By a treating system of this construction it has been achieved that in case of brief suspensions of the operation of the station preceding the conveyor means concerned, the speed of this station will be increased automatically when it starts work after the break, and in the same way a succeeding station may be retarded if the break is so long that the number of objects held between the two stations is reduced too much. If it is the succeeding station that is stopped temporarily, the preceding station will automatically reduce its speed when the accumulation of objects in the storage means exceeds the permissible, or the succeeding station will operate at increased speed when it starts after the break, so that the number of objects may be reduced to normal as fast as possible. By this arrangement the whole system will work effectively to capacity all the time, and practical tests have shown that it is possible to obtain an overall increase of the productive capacity which is so large that the savings more than outbalance the costs incurred by the installation of the specific arrangements taught by the invention.

In order to obtain precisely the regulation desired in any given situation the movable member of the differential gear of the system may be adapted for linear displacement and be connected to a curve section cooperating with a rotatable or displaceable operating means associated with the said regulating device.

To ensure that the automatic regulation of the working speed in exceptional circumstances, normally of very short duration, can be put out and replaced by manual operation, the coupling between the operating means and the regulating device is releaseable to permit the regulating device to be operated manually and independent of the movable member of the differential gear.

In a treating system of the type concerned here control is often provided along the conveyor means between two treating stations. By means of this control objects may be sorted out, and provision must then be made to secure compensation for the objects sorted out, and this has been achieved according to the invention by providing at either side of a sorting sta-

tion an automatically counting device coupled to a primary auxiliary differential gear and adapted to register the number of objects sorted out. The output shaft of the said primary auxiliary differential gear and the counting device disposed between the conveyor means and the succeeding treating station are coupled to a secondary auxiliary differential gear for summing up the recorded values, while the output shaft of the secondary auxiliary differential gear is coupled to one side of the main differential gear, the other side of which is coupled to the counting device located between the conveyor means and the preceding treating station. The primary auxiliary differential gear will record the number of objects that have been sorted out, and by means of the secondary differential gear this number will be added to the number recorded by the counting device between the conveyor means and the succeeding treating station, and thus the automatic speed regulation will be maintained both in the preceding and in the succeeding station irrespective of variations caused by the sorting out.

The working speed of the treating station preceding and/or succeeding the conveyor means is thus regulated by the sum total of objects before or after the sorting station.

The invention will be explained in the following with reference to the drawing, in which:

FIG. 1 illustrates a differential gear according to the invention for use in a treating system according to the invention, and

FIG. 2 shows a treating system according to the invention.

FIG. 1 shows a differential gear 1 comprising two parallel shafts 2 and 3 rotatably mounted at both ends. The shaft 2 has a projecting journal 4 and is threaded, while the shaft 3 has a longitudinally extending groove or bead 5 and a projecting journal 6. On the shaft 2 is mounted a gearwheel 7 provided with an internal thread corresponding to the shaft thread and guided in a crossbar 8 serving also as guide for a gearwheel mounted to be axially slideable on the shaft 3 and secured against rotation relatively to the shaft by means of a projection or a slot cooperating with the groove or bead 5.

The crossbar 8 is rigidly connected to a slide 10 which is slidably mounted on a guide 11 and supports a curved member 12 cooperating with a reel 13 on a regulating arm 14 which is rotatably mounted about a journal 15 and is actuated by means of a spring 16 to rotate clockwise, whereby the reel 13 will be pressed against the curved disc 12. To the journal 15 is secured a disc 17 provided with a projection 18 serving to engage a projection 19 on the arm 14. The disc 17, moreover, is caused to rotate by a spring 20 which is so disposed and secured to the arm 14 that it holds the abutments 18 and 19 in contact with one another. The disc 17 moreover supports an operating handle 21.

The two journals 4 and 6 are adapted for connection to each one of the counting devices, and their direction of rotation and the pitch of the thread of the shaft 2 are adapted to cause the two shafts to rotate in opposite directions and at equal speed when the two counting devices register the same number, so that the two gearwheels 7 and 9 will rotate without being axially displaced and without axial displacement of the crossbar 8 and the curved member 12. But if a difference occurs in the registrations of the two counting devices the rotatory speeds of the two gearwheels 7 and 9 will be different, and the cooperation between the gearwheel 7 and the thread of the shaft 2 will cause displacement of gearwheel and the crossbar 8 whereby the curved member 12 will be displaced and the arm 14 rotated so that also the shaft 15 will rotate.

This shaft may in any convenient manner be coupled to the regulating means for regulation of the working speed of a preceding and/or succeeding treating station, and these regulating means may be electrical, pneumatic, mechanical or other expedient devices. Also, the connection between the journals 4 and 6 and the pertaining counting devices may be provided in any convenient manner, for instance by means of a rotatable shaft, and may be a hydraulic connection or it may be established as an electrical motion transmission. It will be

75

obvious that when there is a certain stock of objects between the two counting devices connected to the journals 4 and 6, the crossbar 8 will remain stationary as long as this stock is maintained constant, but as soon as the supply or takeoff varies so as to affect the stock between the two counting devices, the crossbar will move and thus partly indicate that a change of the stock has set in and partly indicate that a change of the stock has set in and partly actuate automatically the regulating means that serve to adjust the working speed of a preceding and a succeeding treating station.

FIG. 2 shows a system comprising two treating stations, for instance a bottle rinsing assembly 22 and a bottle filling assembly 23. Between these two assemblies there is a conveyor path 24 with two sorting out stations 25 and 26 disposed in parallel and interposed in the conveyor path 24.

At either end of the sorting station 25 there is a counting device, 27 and 28 respectively, and through lines, 29 and 30 respectively, and coupling means, 31 and 32 respectively, the counters are connected to each one of the primary shafts of a traditional differential 33, the directions of rotation of the two primary shafts being selected so that a gearwheel 35 coupled to the output gearwheel 34 of the differential will register the difference between the numbers registered by the counters 27 and 28. In the same manner the sorting station 26 is associated with counters 37 and 38, lines 39 and 40, coupling means 41 and 42, a differential 43 with the output gearwheel 44 and coupled thereto a gearwheel 45 indicating directly the number of objects that have been sorted out at the sorting station 26.

The two gearwheels 35 and 45 are rotating in the same direction and are coupled to each one of the primary shafts of a further differential 46 with an output gearwheel 47 and coupled thereto a gearwheel 48, which will thus register the sum total of the objects sorted out at the two sorting stations 25 and 26. Moreover, the primary shafts of a differential 49 are coupled partly to the gearwheel 48 and partly, through the coupling member 50 and a line 51, to a counter 52 disposed between the conveyor path 24 and the succeeding filling station 23. The primary shafts of the differential 49 are rotating in the same direction, and the number of objects sorted out and recorded by the gearwheel 48 is therefore added to the number registered by the counter 52, so that the output gearwheel 53 of the differential 49 will transmit to a gearwheel 54 a number corresponding to the number of objects received by the succeeding filling station plus the objects sorted out.

Immediately at the point of transition between the bottle filling station 22 and the conveyor path 24 there is a counter 55 connected through a line 56 and a coupling member 57 to one shaft 103 of a differential 101 of the type illustrated in FIG. 1. The other shaft 102 of the differential 101 supports the said gearwheel 54 and is moreover provided with a thread for cooperation with the internal thread of the gearwheel 107 which is in engagement with a gearwheel 109 which is displaceably but not rotatably mounted on the shaft 103 by means of a longitudinal groove or bead 105. The two gearwheels 107 and 109 are guided in a crossbar 108 support-

ing an operating projection 112 cooperating with a regulating device 113 which in turn is connected through a line 114 to an adjustment member 115 for the working speed of the station 22.

- 5 1 claim:
1. A system for treating uniform objects and comprising a plurality of treating stations provided with automatic feeding and conveyor means between successive stations, said conveyor means comprising storage means for the objects to be treated, characterized in that between a station and the succeeding storage means and between the storage means and the succeeding station there is an automatic counting device for counting the objects, that the two counting devices are coupled each to one side of a differential gear provided with a movable member for recording the difference between the numbers of objects registered by the two counting devices, and that the movable member of the differential gear is coupled to a regulation device for the working speed of the preceding and/or the succeeding treating station.
  2. A treating system according to claim 1, characterized in that the movable member of the differential gear is adapted for linear displacement and is connected to a curved member cooperating with a rotatable or displaceable operating means connected to the said regulating device.
  3. A treating system according to claim 2, characterized in that the coupling between the operating means and the regulating device is releasable to permit the regulating device to be operated manually independent of the movable member of the differential gear.
  4. A treating system according to claim 1, in which a sorting out of objects is effected along the conveyor means between the two treating stations, characterized in that at either side of a sorting station there is an automatic counting device coupled to a primary auxiliary differential gear and adapted to register the number of objects sorted out, that the output shaft of said primary auxiliary differential gear and the counting device located between the conveyor means and the succeeding treating station are coupled to a secondary auxiliary differential gear for summing up the recorded values, and that the output shaft of the secondary auxiliary differential gear is coupled to one side of the main differential gear, the other side of which is coupled to the counting device located between the conveyor means and the preceding treating station.
  5. A differential gear for a treating system according to claim 1, characterized in that it comprises two parallel shafts rotating in opposite directions and each provided with means for being coupled to a counting device, one shaft supporting a gearwheel which is axially slidable but not rotatable on the shaft, the other shaft being provided with a thread in which runs a gearwheel which is provided with a threaded hub and which is in engagement with the first-mentioned gearwheel, the two gearwheels being mounted in a displaceable slide forming the movable member of the differential gear or an integral part thereof.
